[57] ABSTRACT

A switch having at least one pair of fixed contacts and at least one pair of movable contacts adapted to cooperate with these fixed contacts, the movable contacts are connected with each other by fuse means and they are supported together with these fuse means by a supporting plate which is movable between a closed position nearest to the fixed contacts and an open position farthest to the said fixed contacts. When at the open position the supporting plate may be turned on itself through 180° so as to bring the fuse means on what is now its outer side, where they are separated from the live parts of the switch by the supporting plate itself. The switch may then be brought to an ineffective closed position for which the supporting plate wholly covers the fixed contacts and forms a closure for the open side of the switch casing.

The fuse means of each pair are preferably in the form of a removable fuse cartridge having end blades which constitute the movable contacts.

ELECTRIC SWITCHES EQUIPPED WITH FUSE MEANS

The present invention relates to switches equipped with fuse cartridges.

Such switches are generally so arranged that the fuse cartridges can only be removed and exchanged when the mechanical contacts of the switch are open. But of course the operator should take care not to touch live parts adjacent to the cartridges.

It is an object of the present invention to provide a switch of the kind above referred to in which the fuse cartridges may be brought to a position wholly exterior to the switch casing itself, in such manner that they may be removed or replaced without any risk for the operator.

In accordance with the invention the fuse cartridges are carried by a movable supporting plate, their end blades cooperating with fixed contacts carried by a stationary base frame so as to form the movable contacts of the switch, and at the open position of the latter, i.e., when the movable supporting plate is farthest from the fixed contacts, the said supporting plate may be turned through 180° in such manner that the fuse cartridges may be situated on what is now the outer side of the said supporting plate. The supporting plate may be locked at this overturned position and its actuating mechanisms may again be operated to bring it to its position nearest to the fixed contacts for which it substantially covers the latter. The operator may then access to the fuse cartridges without any risk of touching live parts. At this position the supporting plate may even form the closing member of a casing surrounding the live parts of the switch which are thus wholly unaccessible.

In the annexed drawings:

FIG. 1 is a perspective view of an embodiment of a disconnecting switch according to the invention, the parts being illustrated at the closed position of the switch.

FIG. 2 is a view similar to FIG. 1, but showing the switch at the open position.

FIG. 3 reproduces FIG. 2, but with the movable supporting plate overturned to expose the fuse cartridges.

FIG. 4 also shows the switch with its movable supporting plate overturned, but after the said plate has been moved towards the fixed contacts of the switch, i.e., when the switch has been ineffectively "closed."

FIG. 5 is a longitudinal section taken along line V—V of FIG. 1.

FIG. 6 is an exploded perspective view showing the detail of one of the securing devices by means of which the fuse cartridges are attached to the movable supporting plate.

FIG. 7 is an enlarged section showing the detail of the device by means of which the movable supporting plate may be locked with one of its actuating carriages.

FIG. 8 is a detailed section of the locking system for the actuating lever of the switch.

FIG. 9 is an enlarged fragmental view in elevation illustrating the auxiliary pre-rupturing contact system associated to the main contacts of the switch.

FIG. 10 is an exploded perspective view showing the essential members of this last system.

FIG. 11 indicates in a very diagrammatical manner how an arc extinguishing device may be associated with the main contacts of the switch.

FIG. 12 shows a modified embodiment of the actuating means of the switch.

The switch illustrated in FIG. 1 comprises a frame formed of two lateral casings 1 and 2 which are appropriately connected with each other by two stays 3 (FIG. 5). These casings have turned edges such as 1a adapted to be secured to suitable supports, such as C-shaped irons 4. Each casing contains a quick-acting mechanism, these mechanisms being operated by a common transverse shaft 5 which may be actuated by a lateral hand lever 6.

Insulating blocks 7 (FIG. 5) are mounted on each stay 3, each of these blocks carrying one of the fixed contacts 8 of the main contact system of the switch. The fixed contacts 8, which may be of any suitable type, are adapted to cooperate with the terminal blades 9 of the fuse cartridges 10 which thus complete the circuit between the sets of fixed contacts respectively carried by stays 3.

The fuse cartridges 10 are attached to a movable supporting plate 11, of substantially rectangular shape, made of an appropriate insulating material and having each of its lateral sides connected with a carriage 12 slidable in guides 1b, 2b provided in the facing sides of casings 1 and 2. In FIG. 2 wherein the outer side of casing 1 is in part broken, it may be seen that carriage 12 is pivotally connected with a connecting rod 13 actuated by the corresponding quick-acting mechanism. It will be understood that with such an arrangement actuation of lever 6 causes supporting plate to move in a direction perpendicular to the plane of stays 3 (or of irons 4) between a "closed" position for which the terminal blades of fuse cartridges 10 engage fixed contacts 8 (position of FIGS. 1 and 5) and an "open" position for which these terminal blades are spaced from the said fixed contacts (position of FIG. 2).

Each fuse cartridge is removably secured to supporting plate 11 by means of the lugs 14 conventionally provided at each end of the body of such cartridges. For this purpose, and as shown in FIG. 6, plate 11 is formed in front of each lug such as 14, with a recess 11a which contains a blade spring 15 having the shape of an Ω. The rectangular opening of recess 11a receives a cover 15 having an aperture 16a in the form of a button hole, comprising a wider portion for passage of lug 14 and a narrower portion the width of which corresponds to the distance between the bottoms of two opposed lateral notches 14a provided in the said lug. The two lugs of each cartridge are pushed into the wider portion of the apertures 16a of the corresponding covers, whereby they enter the central portion of the corresponding springs 15, and they are thereafter pushed longitudinally into the narrower portion of apertures 16a while spreading apart the branches of the spring between which they are thus resiliently retained.

It will be noted that supporting plate 11 includes in front of the central portion of each fuse cartridge 10 a window 11c through which the cartridge body may be seen, as for instance for checking the indications which may be printed thereon, or for observing the lateral indicator button provided in some types of fuse cartridges to indicate that the fusible elements have "blown." Windows 11c are protected by transparent plates 17.

It is known that in other types of cartridges the indicator member comprises a tube which protrudes longitudinally from one of the heads of the cartridge in order

to actuate a microswitch or like alarm contact. In such a case the cartridge should be correctly mounted on supporting plate 11 with its indicator in front of the corresponding micro-switch. For this purpose the supporting plate 11 is provided with inwardly protruding fingers 11d (see FIGS. 3 to 5) which form abutments for the indicators and thus prevent any incorrect mounting of the cartridges. As to the micro-switches adapted to be actuated by these indicators, they have not been illustrated, but it will be understood that they may be mounted on blocks 7, or preferably on an additional stay appropriately disposed between casings 1 and 2.

The supporting plate 11 is so mounted on carriages 12 that it may be rotated through 180° about a transverse axis. For this purpose it is pivoted to the said carriages by means of co-axial trunnions 18 secured to the said plate and rotatably supported in bearings provided in carriages 12. One of the latter further carries a button 19 (FIG. 7) urged towards plate 11 by a spring 20 mounted in a bore 12b of the carriage and which bears against a shoulder 19a of the button rod, this shoulder being slidably guided within bore 12b along an axis parallel to but spaced from the axis of rotation of plate 11. Under the action of spring 20, the end of button 19 is maintained in a blind hole 11e provided in plate 11 and it thus acts as a bolt to lock plate 11 with respect to the carriage. Plate 11 is further formed with a recess having an oblique bottom 11f which may act as a ramp to push back the end of button 19 against spring 20 when plate 11 is rotated about trunnions 18, so as to automatically lock the plate in position with respect to the carriage. In order that plate 11 may be locked at two positions situated at 180° from each other (position of FIG. 2 and position of FIG. 4), the said plate is formed with two bores 11e and with two corresponding recesses 11f.

In normal operation the supporting plate 11 is locked with respect to carriages 12 at such a position that the blades 9 of fuse cartridge 10 may cooperate with the fixed contacts 8. This corresponds to the position of plate 11 in FIGS. 1, 2, 5 and 7. When on the contrary it is desired to have access to the fuse cartridges, the switch is first brought to the open position of FIG. 2 so as to disengage the cartridge blades 9 from the fixed contacts 8, button 19 is pulled laterally to liberate plate 11 and the latter is rotated through 180° about trunnions 18 until it is again locked by button 19 at the overturned position of FIG. 3. The cartridges are now wholly exposed and they may be freely removed and replaced without any risk for the operator.

It is furthermore to be noted that when the supporting plate 11 has thus been overturned, lever 6 may be actuated to bring the switch to what is normally its "closed" position, the supporting plate being brought to its position nearest to the fixed contacts 8, as shown in FIG. 4. It is obvious that since the cartridges are now on the outer side of plate 11, their blades can no more cooperate with the fixed contacts. In other words the switch is ineffectively closed, its circuits being actually open. If the actuating mechanism is locked at such a position, it is impossible for an unauthorized person to rotate the supporting plate. The electric lines controlled by the switch are thus fully safe for any manual operation.

FIG. 8 shows the detail of a possible embodiment for locking the actuating lever 6 by means of a padlock. Lever 6 is formed with a recess 6a on its inner side adja-

cent shaft 5, this recess opening towards casing 1. A substantially flat bolt 21 is slidably guided in recess 6a, as for instance by elongated projections 6b and 6c provided thereon. This bolt has a protruding tooth 21a and it extends upwardly in the form of a lateral actuating lug 21b. A spring 22 attached to bolt 21 and to the lateral wall of recess 6a urges the said bolt into the recess (i.e., towards the right in FIG. 8). Casing 1 carries a lateral plate 23 formed with two slots such as 23a disposed in front of the respective end positions of lever 6. Lever 6 further has a transverse hole 6d which crosses the bottom of recess 6a.

Under the action of spring 22 bolt 21 is normally maintained at its inoperative position for which tooth 21a does not protrude towards casing 1 and plate 23. But by acting on lug 21b it is possible to push the said bolt towards the left in FIG. 8 against the action of spring 22 and thus to drive tooth 21a into one of slots 23a. If now a padlock is passed through hole 6d, bolt 21 is maintained in position and lever 6 remains locked.

The system of auxiliary pre-rupturing contacts illustrated in FIGS. 9 and 10 comprises a cam 25 mounted on shaft 5 within casing 2 to act on the turned edge 26a of a slide 26 which is guided in a direction parallel to that of carriages 12 (or horizontally in FIGS. 1 to 5). There is provided for this purpose a fixed plate 27 having two protruding lugs 27a which retain slide 26 laterally. Slide 26 is further formed with an elongated rectangular aperture 26b in which a compression spring 28 is disposed. The latter takes rest against a tooth 27b raised from plate 27 and which passes through aperture 26b to complete the guiding of the slide. Slide 26 actuates an insulating support 29 which carries movable contacts 30 adapted to cooperate with fixed contacts 31 mounted on an insulating base 32 secured in any appropriate manner not shown to plate 27 or to its protruding lugs 27a. These contacts are protected by a transparent cover 33. In the example illustrated support 29, of elongated rectangular shape, is slidably guided by cover 33 and it is connected with slide 26 by a pin 29a secured to the said support and engaged into a hole 26c of the slide.

As aforesaid, lever 6 actuates carriages 12 through quick-acting mechanisms not illustrated. Such a mechanism comprises in the conventional manner a spring which the driving member of the mechanism compresses or extends until the said spring is permitted to act on the driven member to snap same from one of its positions to the other. There exists therefore for lever 6 an initial period during which it rotates shaft 5 without actuating carriages 12. Cam 25 is so arranged that it moves slide 26 during this initial period to close the auxiliary contacts 30-31. The circuits controlled by these contacts are therefore already closed when the main contacts of the switch (i.e., blades 9 and contacts 8) open. Auxiliary contacts 30-31 are used to actuate a circuit breaker disposed in series with the present switch. With such an arrangement the switch always opens under no load condition and its main contacts 9 and 8 can never be damaged in spite of their low rupturing capacity.

When it is desired to increase this rupturing capacity, it is possible to secure to the switch frame, between the fixed contacts 8 and the supporting plate 11, a number of small spaced parallel plates 34 (FIG. 11) formed with slots 34a for passage of blades 9. When the switch opens, blades 9 pass through slots 34a as soon as they

are disengaged from contacts 8, in such manner that the electric arc which appears between the blades and the fixed contacts is effectively cooled by plates 34 and is therefore rapidly extinguished. Of course plates 34 should be metallic and appropriately insulated from each other and from the switch frame.

FIG. 12 illustrates a modification wherein shaft 5 carries a conical toothed segment 35 which meshes with another corresponding segment 36 mounted on a lateral shaft 37 rotatably supported by a bracket 38, the said shaft carrying an actuating hand wheel 39. Such an arrangement, which dispenses with lever 6, may be of advantage when it is desired to actuate the switch from the front or from the rear in FIG. 1.

The poles of the switch are preferably protected by transparent covers, respectively 40, 41, which may be removably supported by lateral plates 42. These covers may extend somewhat under the movable supporting plate 11 in which case they are provided with slot such as 40a for passage of blades 9. When the switch is ineffectively "closed" (FIG. 4), the supporting plate 11 plays the role of a front cover for the casing formed by covers 40, 41 and plates 42, whereby the live parts of the switch are wholly enclosed and protected.

I claim:

1. An electric switch comprising:

a frame;

at least one pair of fixed contacts carried by said frame, said fixed contacts being insulated from each other;

at least one pair of movable contacts insulated from each other, to respectively cooperate with said fixed contacts;

fuse means to connect with each other the contacts of said pair of movable contacts;

a movable supporting plate to support said movable contacts and said fuse means, said plate having a first side and a second side;

attaching means to attach said movable contacts and said fuse means to said first side of said movable supporting plate;

driving means on said frame to displace said movable supporting plate between a closed position nearest to said fixed contacts and an open position farthest from same;

pivoting means to pivotally connect said supporting plate to said driving means; and

locking means to lock said supporting plate with respect to said driving means at a first orientation for which said first side of said plate faces said fixed

5

contacts in such manner that said movable contacts may engage said fixed contacts at said closed position of said plate and be spaced from same at said open position of said plate, and a second orientation at substantially 180° from said first orientation, and for which said movable contacts are separated from said fixed contacts by said supporting plate at both said closed and open positions of same.

2. In a switch as claimed in claim 1, said fuse means being in the form of a fuse cartridge having a pair of opposed terminal blades, with said blades forming said movable contacts.

3. In a switch as claimed in claim 2, said fuse cartridge having a body intermediate said terminal blades, said attaching means being interposed between said body and said supporting plate.

4. In a switch as claimed in claim 3, said attaching means comprising lugs carried by said cartridge body and resilient clamping members carried by the first side of said supporting plate to removably retain said lugs.

5. In a switch as claimed in claim 1, said movable supporting plate being made of an insulating material.

6. In a switch as claimed in claim 1, said pair of fixed contacts defining a longitudinal axis and said driving means comprising:

a pair of movable lateral carriages disposed each side of said fixed contacts with said pivoting means being co-axially interposed between said supporting plates and each of said carriages and with said locking means being interposed between said supporting plate and one at least of said carriages; means to guide said carriages along substantially parallel paths substantially perpendicular to the longitudinal axis of said pair of fixed contacts; and actuating means to actuate both carriages in unison.

7. In a switch as claimed in claim 6, said pivoting means defining an axis of rotation for said supporting plate on said carriages; and said locking means comprising bolt means slidably movable on said one of said carriages along a line substantially parallel to and spaced from said axis of rotation, resilient means to urge said bolt means towards said supporting plate, and depressions provided in said plate to cooperate with said bolt means at said first and second orientations of said plate.

8. In a switch as claimed in claim 1, said frame embodying a casing having an open side and said plate closing said open side of said casing when at said second orientation and at said closed position.
